[57] **CLAIM**

The ornamental design for a night light, as shown and
described.

DESCRIPTION

FIG. 1 is a perspective view as seen from the top, front
and right side of a night light;

FIG. 2 is a perspective view as seen from the top, rear
and right side of the night light of FIG. 1;

FIG. 3 is a top plan view thereof;

FIG. 4 is a front elevational view thereof;

FIG. 5 is a right side elevational view thereof, the left
side being a mirror image;

FIG. 6 is a rear elevational view;

FIG. 7 is a bottom plan view; and,

FIG. 8 is perspective view similar to FIG. 2 wherein
broken lines are for environmental purposes only, and
do not constitute a part of the claimed design.

The characteristic features of this design reside in the
indentation and opening in the rear surface, the rear
indentation having a dimension at least that of a conven-
tional wall plate as shown in FIGS. 2, 6, and 8.

The interior lamp and connector prongs are shown in
broken lines in FIGS. 2, 3, 5, 6, 7 and 8 for illustrative
purposes only and form no part of the claimed design.
